GOVERNOR

Ray F. Smith, Des Moines, Iowa, assignor to Ideal Manufacturing Company, Des Moines, Iowa, a corporation of Iowa

Application June 7, 1937, Serial No. 146,720

1 Claim. (Cl. 137—156)

The object of my invention is to provide a governor of simple, sturdy and economical construction for installation on an internal combustion engine, for regulating the speed at which the engine operates.

Another object is to provide a universal mounting for such governor whereby the governor may be mounted upon any engine.

With these and other objects in view, my invention consists in the construction, arrangement and combination of the various parts of the device, whereby the objects contemplated are attained, as hereinafter more fully set forth, pointed out in my claim, and illustrated in the accompanying drawing, in which:

Figure 1 is a perspective view of my governor and universal mounting.

Figure 2 is a detail sectional view taken on the line 2—2 of Figure 1, illustrating the governor and further illustrating the connection thereof with the throttle lever.

Figures 3 and 4 are side elevations illustrating the mounting of the governor on different engines; and

Figure 5 is a perspective view illustrating a different way of mounting the governor.

My improved governor is being manufactured and sold largely for installation upon engines that have been removed from automobiles and are being used as power plants for operating saws, feed grinders and so on. The governor is also available for tractors and trucks.

Broadly speaking, it involves the operation of the throttle valve in accordance with the vacuum in the intake manifold.

In the accompanying drawing I have shown the body of my governor made in two halves shown at 10 and 11. The body members 10 and 11 have adjacent annular flanges 12 and 13 adapted to be locked together by screws 14. The body members are formed with recesses 15 and 16 which register with each other when the body members are fastened together and form a diaphragm chamber.

A diaphragm 17, which may be of any suitable material, for instance a pair of disks of flexible rubber, has its periphery firmly gripped between the flanges 12 and 13 as shown in Figure 2. In the member 10 there is a passage 15' connecting the recess 15 with the atmosphere, thereby setting up atmospheric pressure on one side of the diaphragm 17.

Extending from the recess 16 to the exterior of the body member 11 is a bore or passage 18, the outer part of which is internally screw

threaded as at 19 to receive an adjusting screw 20 on which is the lock nut 21.

In the body member 10 a bore or passage 22 leads from the recess 15 to the exterior of the body. A stem 23 is slidably extended through the passage 22 and has on its inner end a head 24 which is properly secured to the diaphragm 17. A coil spring 25 in the bore 18 extends between the adjusting screw 20 and the head 24. The outer end of the stem 23 is threaded as at 26 to receive one end of a turnbuckle 27. The other end of the turnbuckle 27 is threaded on the rod 28.

In practical use the rod 28 is connected by a link 29 with a throttle arm 30 on the throttle shaft 31 in the fuel passage 32 of an internal combustion engine. A branch passage 33 leads from the passage 18 to the exterior of the body member 11. A tubular fitting 34 is threaded into the outer end of the passage 33 and is connected with a flexible pipe or the like 25, which in use is in turn connected to the intake manifold.

I shall first refer to the operation of my improved governor and shall then turn to the universal mounting.

Assuming that the governor is being installed on an internal combustion engine 36, and that the governor body members have been fixedly mounted, the rod 29 is connected with the throttle arm 30. Then the engine is operated and the turnbuckle is adjusted until the engine is running at the speed which it is desired to maintain for its operation. It should be borne in mind that this is not ordinary idling speed, but is usually a considerably higher speed.

The parts are so adjusted that when the engine thus, without loads, operates at the desired speed, the vacuum will be high enough to hold the head 24 in its lower dotted line position illustrated in Figure 2. Then during the operation of the engine, if a load is imposed upon the engine, the vacuum to which the under side of the diaphragm is subjected will be reduced and the spring 25 will expand to force the diaphragm upwardly, thereby opening the throttle valve and supplying additional fuel to the engine for causing it to speed up so that the proper speed can be maintained.

It is, of course, obvious that the screw 20 can be adjusted to determine the tension under which the spring 25 operates.

Universal mounting

I have provided a universal mounting for my governor. A bar 37 is adjustably fixed to the

body member 10 by means of a cap screw 38. A short angle bar 39 is adjustably secured to the bar 37 by means of a cap screw 40 and is also adjustably connected with another bar 41 by a cap screw 42.

A second short angle bar 43 is adjustably secured to the outer end of the bar 41 by means of a cap screw 44. The angle bar 43 is also connected by a cap screw 45 with a pair of bars 46 and 47. The bar 46 has a series of holes 48, any one of which may be made to selectively receive the cap screw 45. The bar 47 has an elongated slot 49 to receive the cap screw. The bars 46 and 47 have at their outer ends opposite portions 50 and 51 provided with holes 52 and 53 to receive cap screws or the like for fastening them to the head bolts or manifold bolts or other part of an internal combustion engine.

This mounting structure is such that the governor can be conveniently, easily and quickly installed on practically any automobile engine now being manufactured. It will be observed that the bars 37 and 41 are provided with spaced holes 56 and 57 so that the angle bars can be adjustably mounted at various points in the length of these bars 37 and 41.

In Figure 3 I have shown how the supporting bars may be omitted in using the governor on a tractor.

30 The stem 23 is connected by turn buckle structure to the throttle arm 30a. The casing is pivoted to the accelerator rod 59, so as to be hung and supported to move with the accelerator rod for operating the throttle.

35 The movement of the stem 23 is as before explained for permitting the governor to react automatically to intake conditions.

In Figure 4 the governor is shown applied to a Chevrolet. The arms 46 are fastened to the 40 head bolts 60 and project divergently horizontally away. The angle bar 43 and the bar 41 are so arranged that the latter projects rearwardly as shown. The angle bar 39 connects to the bar 37 near the end thereof which is secured to the governor, thus illustrating the great variety of possible arrangements of the parts of the mounting where the governor is so arranged that the stem 23 points horizontally and laterally toward the engine.

50 In Figure 5 there is another arrangement which is obvious from the drawing.

In Figure 4 the Chevrolet engine is indicated at 61 and in Figure 5 the Plymouth engine is indicated at 62.

A device of this kind has a great many advantages. The advantage in using a diaphragm 5 type of operating device is because it can be readily constructed so there is no leak past the diaphragm. The device has such universal adjustment that it can be set to operate an engine at any desired speed, or in case of a tractor, truck or 10 motor car, it can be set so the car cannot travel above a certain speed for which the governor may be adjusted.

It is, of course, obvious from the foregoing description that some changes may be made in the 15 details of construction of my governor, and it is my intention to cover by my claim any modified forms which may be reasonably included within the scope of my claim.

I claim as my invention:

20 In a speed governor for engines, a casing having adjustable attaching means thereon for securing it to an engine in any one of several positions and comprising a pair of external body members positioned face to face having each a 25 recessed portion forming a pocket matching said pocket in the other member, a diaphragm disc sealed between said body members separating said pockets, one of said pockets being exposed to atmospheric pressure and having a bore extending therefrom in axial alignment with the diaphragm and a continuous stem in said bore attached at one end to the center of the diaphragm in axial alignment therewith and at the other end to a throttle valve arm adapted by 30 movement thereof to control the action of the engine, the other of said pockets being sealed from the atmosphere and having a connection therefrom to the intake manifold, a bore in the other said body members in axial alignment with 35 said diaphragm and said stem, a coiled spring in said bore bearing on said diaphragm tending to urge it in a predetermined direction and a threaded adjusting means extending through said other body member to a point outside said member in axial alignment with the spring and stem adapted to permit adjustment of the spring from a position outside said casing.
